UNITED STATES PATENT OFFICE

2,600,825

INDEX TAB

George J. Aigner, Chicago, Ill., assignor to G. J. Aigner Company, Chicago, Ill., a corporation of Illinois.

Application February 4, 1948, Serial No. 6,230

1. Claim. (Cl. 129—16.8)

1

This invention relates to index tabs, and one of its objects is to provide an index tab which may be permanently attached to a file card, separation card or the like without the use of eyelets, rivets or similar fastening means.

Another object is to provide an index tab which may be made of extruded plastic material in indefinite lengths, after which the indefinite lengths of material may be severed into individual index tabs of the required length.

Another object is to provide an index tab with an inclined, transparent index strip holding portion having longitudinally extending grooves at its top and bottom edges, in which the top and bottom edges of the index strip are held.

Another object is to provide a vertically slotted upright wall at the rear or front of the tab adapted to receive the upper edge portion of a card in the slot and permanently secured in said slot by upset portions of one side portion of the slotted wall, which upset portions are forced into apertures or openings in the card.

Another object is to provide an index tab formed of a single piece of plastic material in which the oblique face portion is supported by the upright slotted wall and by a diagonally extending brace which joins with the face portion and with the upright wall at its lower edge, thereby providing a face portion which is braced at its top and bottom edges, whereby the face portion is not likely to become distorted by rough handling.

With these and other objects and advantages in view, this invention consists in the several novel features hereinafter fully set forth and more particularly defined in the appended claims.

The invention is clearly illustrated in the drawing accompanying this specification, in which:

Fig. 1 is a perspective view upon an enlarged scale of an index tab embodying a simple form of the present invention and attached to a fragment of a file card;

Fig. 2 is a greatly enlarged view in vertical cross section of the index tab and card taken on the line 2—2 of Fig. 1;

Fig. 3 is a rear elevation of the index tab fastened to a fragment of a card;

Fig. 4 is a rear elevation of a slightly modified form of index tab fastened upon a fragment of a card; and

Fig. 5 is a greatly enlarged detail fragmental vertical section taken on the line 5—5 of Fig. 4.

Referring to said drawing, and first to Figs. 1 to 3 inclusive, which are merely illustrative of one

embodiment of the invention, the reference character 6 designates a fragment of a file card, separation card or the like usually of rectangular form and composed of cardboard, fiber or other suitable material, and 7 designates the index tab generally and preferably composed of extruded plastic material such as Celluloid, vinyl, Bakelite or the like.

The index tab is formed with a curved, upwardly and rearwardly inclined face portion 8 adjacent the inner face of which is held an index strip 9 on which is printed, written or otherwise impressed suitable data or other indicia.

The top and bottom edges of the face portion are rounded as at 10, 11 to provide round grooves 12, 13 in which the top and bottom edges of the index strip are received. Preferably, the index strip is of a length from top to bottom that the top and bottom edges thereof will press against the curved faces of the grooves 12, 13 and thereby place the index strip under slight pressure against the inner side of the face portion 8 to thereby hold the index strip tightly against said face portion.

Projecting down from one of the edges of the face portion, preferably the upper curved edge 10, is a vertically and longitudinally slotted upright wall 14, the upper end portion 15 of which is made thinner than the slotted portion and merges into the curved edge 10 of the face portion. Face portion 8 is equal in thickness to the upper end portion 15, and is thinner than the slotted upright wall 14. Integrally joined to and extending between the curved edge 10 and the side portion 20 of the slotted wall 14 is a diagonally extending brace 16 which is of greater thickness than said face portion, and provides a rigid connection between the lower edge of the face portion and the slotted wall. The upper edges 17, 18 of the slotted wall 14 and brace 16 form shoulders that co-operate with the curved top and bottom edges 10 and 11 of face portion 8 to provide the grooves for receiving the top and bottom edges of an index strip.

The two side portions 19, 20 of the slotted wall 14 are straight and parallel and receive the upper edge portion 21 of the card 6 between them. The lower edge 22 of the side portion 19 of the slotted wall is beveled off as shown and the lower edge 23 of the brace is also beveled off so as to avoid any abrupt shoulders or edges between the card and the index tab.

The edge portion 21 of the card which is disposed in the slot between the side portions 19, 20 of the slotted upright wall is formed with one

or more perforations as at 24 and the material of the side portion 19 of the slotted wall is indented into said perforations as at 25 by any suitable process, thereby preventing the index tab from being pulled off the card except, of course, upon the application of great force.

In the modified form of the invention illustrated in Figs. 4 and 5, the card 6a is formed adjacent its upper edge with an elongated slot 24a which preferably extends parallel with the upper edge of the card 6a, and the side portion 19a of the slotted wall 14a is formed with an elongated indentation 25a which extends through the slot 24a and thus prevents the index tab from being pulled off the card except, of course, upon the application of great force.

The indentations 25 and 25a may be formed by an electronic method, if desired, or may be formed by the application of heat to the index tab and the indentations made with a suitable tool. With the use of the means disclosed for fastening the index tab to the card, no unsightly protruding rivet heads are used.

The index tab may be composed of extruded plastic material of indefinite length severed into individual index tabs of the desired length. If desired, the material may be tinted, provided the face portion is left transparent so that the index strip therebelow may be easily read.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

An index tab for mounting on the edge of a supporting card or the like composed of a single piece of material and comprising a transparent inclined face portion having curved top and bottom edges, a vertically and longitudinally slotted upright wall connected to and extending down from the upper curved edge of the face portion,

said slotted wall being adapted to receive an edge of a supporting card on which the tab is to be mounted and having an upper edge of greater thickness than said face portion forming a shoulder, and intermediate portion of the outer side of the slotted wall being formed as an indentation extending across the slot and terminating adjacent the other side of such wall for engagement with the edges of an opening in such a card, and a diagonally extending brace member of greater thickness than said face portion extending between and merging into the lower edge of the face portion and the adjacent side of the slotted wall, the upper edge of said brace member forming a shoulder, the shoulders formed by the upper edges of said brace member and said slotted upright wall co-operating with the curved top and bottom edges of said face portion to provide grooves for receiving the top and bottom edge portions of an index strip.

GEORGE J. AIGNER.
